Fig. 1

Fig. 7

FIG. 1 is an isometric view of a cabinet showing my new design;

FIG. 2 is a front elevational view thereof;

FIG. 3 is a top plan view thereof;

FIG. 4 is a bottom plan view thereof;

FIG. 5 is a side elevational view thereof;

FIG. 6 is a rear elevational view thereof; and

FIG. 7 is an enlarged fragmentary detailed view of the portion of the cabinet encircled by the line 7—7 of FIG. 1.

The dominant features of my design reside in the specific drawer pulls in combination with the indented front corners as best illustrated in FIG. 7.

I claim:

The ornamental design for a cabinet, as shown and described.
